(57) **CLAIM**

The ornamental design for a printer cartridge, as shown and described.

DESCRIPTION

FIG. 1 is a front view of a printer cartridge showing our new design;

FIG. 2 is a top view thereof;

FIG. 3 is a left side elevational view thereof;

FIG. 4 is a right side elevational view thereof;

FIG. 5 is a rear view thereof;

FIG. 6 is a bottom view thereof;

FIG. 7 is a top perspective view thereof;

FIG. 8 is a bottom perspective view thereof;

FIG. 9 is an enlarged right side elevational view of the printer cartridge with a handle in a second position;

FIG. 10 is an enlarged partial perspective view of the upper right side thereof;

FIG. 11 is an enlarged partial perspective view of the lower right side thereof;

FIG. 12 is an enlarged partial perspective view of the upper left side thereof; and,

FIG. 13 is an enlarged partial perspective view of the lower left side thereof.

The broken lines depict environmental subject matter only and form no part of the claimed design.
